CHARLES B. MCLEER AND JOSEPH F. MCLEER, OF BROOKLYN, NEW YORK, ASSIGNEES
TO ELECTRIC CARRIER COMPANY, OF DELAWARE.

ELECTRIC TRANSPORTATION SYSTEM.

1,089,778.

Specification of Letters Patent. Patented Mar. 10, 1914.

Application filed May 26, 1911. Serial No. 629,603.

To all whom it may concern:

Be it known that we, CHARLES B. MCLEER and JOSEPH F. MCLEER, citizens of the United States, and residents of Brooklyn, New York, have invented certain Improvements in Electric Transportation Systems, of which the following is a specification.

One object of our invention is to provide a thoroughly practical and efficient electrical transportation system of the general type described and claimed in the patents to Franklin S. Smith, No. 859,018, and No. 859,019, dated July 2, 1907; it being particularly desired that the stationary as well as the movable elements of said system shall be of a substantial and thoroughly mechanical construction such for example as will meet the requirements of an intercity parcel transfer system, as well as one designed to transport packages between widely separated points of the same building or city. These objects and other advantageous ends we secure as hereinafter set forth, reference being had to the accompanying drawings, in which;

Figure 1, is a vertical longitudinal section of a portion of the inclosing casing and its associated parts forming the stationary element of a transportation system constructed according to our invention; Fig. 2, is a transverse vertical section on the line *a—a*, Fig. 1; Fig. 3, is a side elevation of one of the movable elements forming part of our system; Fig. 4, is an end elevation of the carrier shown in Fig. 3; Fig. 5, is a transverse vertical section of the carrier shown in Fig. 3, the same being taken on the line *b—b*; Fig. 6, is a transverse vertical section, illustrating a double track form of our invention.

Referring to Figs. 1 and 2 of the above drawings, the stationary portion of our transportation system consists of a supporting and inclosing casing 1, preferably in the form of a closed tube supported in any desired or suitable manner upon frames or other foundations (not shown) whose construction may be varied as the requirements of any particular case may dictate. At intervals within this tube are mounted annular supporting ribs 2 lying in transverse planes to brace and strengthen said tube as well as to serve as the means for directly supporting a track or tracks 3 which extend

longitudinally through the tube adjacent the bottom thereof. In addition these ribs also serve to support two pairs of rails or tracks 4 and 5 mounted at opposite sides of the tube 1 and there are also at the top of the latter two conductors 6 and 7 in the shape of bars or rails, electrically insulated from the ribs and therefore from each other, as well as from the tubular casing, by plates of insulating material 8.

Between the side rails 4 is mounted a longitudinally extending laminated bar-like structure 9 electrically insulated from the ribs by a plate or other body of non-conducting material 10, and vertically slotted as shown, for the reception of an electrical conductor 11 which with it constitutes one of the secondaries or fixed motor members of the electrical part of the system. Said conductor 11, which broadly considered, forms a winding and will hereafter be designated as such, is preferably constructed of an elongated copper sheet or bar punched to provide a series of vertical slots for the reception of the portions between the slots of the bar 9; it being noted that this structure is thus in effect composed of a series of copper bars mounted in the slots of the said bar 9, with longitudinally extending copper strips or bars electrically connecting their adjacent ends. Similarly, between the side bars or rails 5 opposite the rails 4, there is mounted a second longitudinally extending laminated and slotted bar 12 insulated from the supporting ribs by non-conducting material 10 and having mounted in its slots what may be described as a developed squirrel cage winding 13 similar to that provided by the conductor 11 of the bar 9. It is understood that the various rails as well as the laminated bars 9 and 12 and the conductors 6 and 7 are connected to their supporting rib structures 2 in any desired and suitable manner necessary to provide a substantial and practical device, although such detail features have been omitted from the present drawings since, in themselves, they constitute no part of the present invention.

The movable elements of the system, of which there may be any desired number, each preferably consists of two parallel end plates 14 and 15 connected by two parallel side plates 16. Said end plates may be formed with lugs 17 extending toward each

other at the lower portions thereof for the purpose of supporting a suitable floor or for holding an independent container 17^a in which are placed articles to be transported.

As shown in Figs. 3 and 4, each of the end plates 14 and 15 has two pairs of outwardly projecting bearing brackets 18 in which are journaled spindles or axles 19 carrying flanged wheels 20. These latter project below the plane of the lowest portions of the carrier structure and are spaced to operate on the bottom tracks or rails 3. Two other pairs of outwardly projecting bearing brackets 21 are mounted at each side of the top portions of each of the end plates 14 and 15, although in this instance each pair of said brackets is electrically insulated from the frame of the carrier and from the adjacent pair of brackets by a sheet of insulating material 22. Each of these brackets 21 has an upwardly opening slot carrying a bearing 23 mounted on a spring 24, and the bearings of each pair of the brackets serve to support a spindle 25 carrying a contact wheel 26 projecting above the top of the carrier so as to engage one of the conductor rails 6 or 7 as the case may be.

Each of the bearings 23 for the spindles of the conductor wheels 26 and the casting of which the brackets 21 preferably though not necessarily form a part, are electrically connected by means of a flexible conductor 35 27. Extending longitudinally of the carrier and mounted on the side members 16 thereof are two laminated slotted structures 28 and 29 held in place by any suitable means and provided with windings 30 arranged in the manner well known in the art and common in various forms of induction motors; it being understood that these laminated structures 28 and 29 with their windings constitute motor members forming the primaries 40 45 of an alternating current motive power device of which the bars 9 and 12 with their windings form the secondaries. Each of the sets of windings 30 is preferably in electrical connection with the brackets 21 at opposite ends of the carrier and on that side thereof adjacent its particular laminated structure 28 or 29, as the case may be.

In order to properly position the carrier within the casing 1 relatively to the various fixed structures mounted therein, we provide it with upper and lower sets of guide rollers or wheels 31 and 32, mounted on spindles carried in suitable bearings formed in lugs projecting from the side members 16; there being in the present instance three upper and three lower wheels on each side so placed as to be directly opposite and capable of engaging the rails or tracks 4 and 5 extending along the sides of the casing 1.

65 The particular apparatus described and

illustrated having been designed for a system operating on three-phase alternating current, two ends of the winding 30 are respectively connected to the two contact wheels 26 at one end of the carrier, and also with the wheels 26 at the opposite end of the carrier, so that each winding end is connected to a wheel at each end of said carrier. The third end of the winding in the slots of the structures 28 and 29 is grounded on the frame of the carrier and is hence in electrical connection with the supporting wheels 20. Under operating conditions, therefore, the rails 3, 6 and 7 are respectively connected to the three conductors of a three-phase supply circuit, so that when the carrier is properly mounted in the casing 1 and the necessary controlling switches are closed, it is caused to move longitudinally through said casing by reason of the reaction occurring between the stationary motor members 9-11, and 12-13 carried by the casing, and their co-acting motor members 28 and 29 with the windings mounted therein supported upon the carrier structure. Under these conditions the rails 3 not only support the movable carrier but also serve as one of the conductors for supplying current to the windings of said carrier. The side rollers or wheels 31 and 32 co-act with the side rails or tracks 4 and 5 to keep the carrier properly centered in the casing and hence maintain its slotted structures 28 and 29 with their windings at the proper distance from the laminated bars 9 and 12 which, as above noted, extend continuously through the casing.

By the use of the springs 24, the contact wheels 26 are maintained in electrical connection with the tracks 6 and 7 under operating conditions in spite of any slight irregularities in the latter, and the continuity of such connection is rendered more certain by reason of the fact that the front and back wheels on the same side of the carrier are connected in multiple. In the present instance we have illustrated a containing structure 17^a mounted within the rectangular frame defined by the members 14, 16 and 15 and resting upon the flanges or lugs 16 and 17. It is, however, obvious that the form of the frame, as well as the shape of the container carried thereby, may be widely varied to suit different conditions without in any way departing from our invention.

As shown in Fig. 6, the casing may be given the form indicated at 1^a so as to accommodate two complete sets of supporting tracks 3, fixed motor elements 9 and 12 and the various conducting and guiding tracks. For this purpose the ribs are given the form indicated at 2^a so as to properly support these various members and in the upper and lower spaces between the elongated cylindrical spaces for the reception

of the carriers, we may place conduits 41 and 42 for the reception of electrical conductors or for any purpose.

While the two sets of fixed motor elements 5 and those portions of the casing, which, while belonging to the two sets of tracks, are immediately adjacent to each other, may be constructed as shown in Fig. 2, we may provide a single fixed motor member having 10 windings on its opposite faces and support the same in position to coöperate with the windings of a carrier on either of the two tracks. In such case we mount a single longitudinally extending laminated structure 15 43 on the supporting structure provided by the ribs and construct it with slots in its two opposite vertical faces. Each of these sets of slots is provided with conductors or windings in the form of a punched cast or 20 slotted copper or other conducting plate as in the cases heretofore described.

With this arrangement of parts, one set of the tracks 3 and its associated motor elements, etc., may be designed for the reception 25 of carriers traveling in one direction while the other set of tracks and its coöperating parts receives carriers traveling in the opposite direction.

It will be noted that the winding on the 30 laminated members 28 and 29 may be of any suitable single or polyphase type, although in the present instance it is preferably of a three-phase form.

While we have referred to the movable 35 members of our system as a "carrier," it is to be understood that it is not necessarily so constructed as to itself invariably serve to directly support material to be transported, since it may without departing from our invention 40 be used as a motor car or locomotive in connection with one or more trailers.

The motor members or elements supported on the opposite sides of the carrier serve in this position to balance the same to 45 some extent on its supporting track and are maintained at the necessary predetermined distances from the adjacent surfaces of the motor members 9 and 12 with their closed circuit winding so as to insure the proper 50 operation of the system from an electrical standpoint.

The various supporting, guiding and current collecting wheels or rollers have their spindles preferably mounted in ball bearings 55 so as to reduce the frictional losses to a minimum.

While the fixed motor members are shown as mounted along the sides of the casing, it is obvious that they may be placed in other 60 positions and the motor members of the carrier correspondingly shifted without departing from our invention.

We claim:—

1. The combination in an electric transportation system of a casing having interior

ribs providing passageways; a track in each of said passageways carried by said ribs; motor members mounted on the ribs on opposite sides of each of said passageways; a carrier having motive power means placed to 70 coöperate with said motor members of the passageways to cause said carrier to be propelled on said tracks through the same; with a conduit mounted on the ribs within the casing but outside of the passageways 75 thereof.

2. The combination in an electric transportation system of a carrier consisting of a container having supporting wheels; laminated structures mounted on opposite sides 80 of said container and provided with windings; contacts on the carrier electrically connected to said windings; a supporting and guiding structure for the carrier; supply conductors placed to be engaged by the contacts on the carrier and connected to a source of alternating current supply; laminated structures mounted adjacent said supporting structure; and closed circuit conductors on said laminated structures. 85

3. An electric transportation system consisting of a supporting structure; a movable carrier; guiding means therefor; and an electric motive power device for actuating said carrier, the same consisting of an elongated laminated and transversely grooved member mounted on the supporting structure; an elongated plate formed of electrical conducting material slotted to form transverse elements and mounted with said 90 elements in the grooves of the laminated member; and windings on the carrier connected to a source of alternating current supply and placed to coöperate with the elongated member to cause movement of said 95 carrier on said guiding means. 100

4. An electric transportation system consisting of two sets of carrier guiding structures; means for supporting the same adjacent each other; a carrier movable on said 110 guiding structures; and motive power means for propelling the carrier consisting of a fixed motor member adjacent each set of guiding structures and a fixed motor member mounted to coöperate with a carrier on 115 either guiding structure; windings on the carrier connected to a source of alternating current supply and placed to co-act with the fixed motor members to propel the said carrier. 120

5. An electric transportation system consisting of an elongated transversely grooved member; an elongated plate formed of electrically conducting material slotted to form transverse elements and mounted with said 125 elements in the grooves of said elongated member; carriers movably mounted to operate adjacent the elongated member, said carriers having windings placed to coöperate with the elongated member and its conduct- 130

ing plate, and a source of alternating current supply connected with said windings.

6. An electric transportation system consisting of an elongated casing; annular supporting ribs within the same; an elongated transversely grooved member of magnetic material extending longitudinally through said casing and supported on the ribs; an elongated plate of electrical conducting material slotted to form transverse conducting elements and mounted with said elements in the grooves of said elongated member; tracks in the casing; and carriers movable on the tracks adjacent the elongated mem-

ber; windings on the carriers placed to co-operate with the elongated member and its conducting plate; and a source of alternating current supply connected with said windings.

In testimony whereof, we have signed our names to this specification, in the presence of two subscribing witnesses.
